DRILL RETAINER

John C. Curtis, Cleveland, Ohio, assignor to The
Cleveland Rock Drill Company, Cleveland,
Ohio, a corporation of Ohio

Application April 25, 1932, Serial No. 607,244

7 Claims. (Cl. 121—32)

The present invention relates broadly to rock drills of the percussion type but is more particularly concerned with improvements in steel or tool retainers therefor.

One of the objects of this invention is to provide a releasable tool retainer which is simple in design, economic of manufacture, and one which is susceptible of ready operation.

Another object is to provide a tool retainer which is so constructed as to prevent the accidental disengagement of the tool or steel from the drill.

Other objects and advantages of the present invention will appear as the description proceeds.

In the accompanying drawing wherein like reference characters indicate like parts throughout the several views:

Fig. 1 is an elevational view partly in section of the lower or front end portion of a rock drill illustrating the tool retainer of this invention attached thereto.

Fig. 2 is a similar view taken at right angles to Fig. 1.

Fig. 3 is an end elevational view of Fig. 1.

Fig. 4 is a view similar to Fig. 3, illustrating the retainer shifted to inoperative position.

Referring now in detail to the drawing, 10 represents the front housing of a rock drill, which is provided with a bore 11, and enlarged counterbore 12. Slidably mounted within the bore 11, there is the shank 13 of a cutting tool 14. The penetration of the shank within the front housing is limited by the engagement of an integral collar 15 with the face or shoulder 16, formed at 35 the intersection of the bore 11 and counterbore 12.

Opening into the counterbore 12 and disposed in parallel alignment with the counterbore 12, there is provided an opening or slot 17, being terminated, toward the face 16, by an enlarged 40 circular recess 18. Diametrically opposed to the slot 17, there is provided a similar slot 19 being connected to the exterior by an opening 20, disposed at right angle from the slot 19. Adjacent the slot 19 and opening 20, the housing 10 is provided with an integral supporting lug 22 45 provided with a transversely disposed recess 23.

The retainer comprises a yoke 24 formed with a substantially semi-circular loop 25. Extending from the ends of the loop 25, there are two integral arms 26 and 27. The arm 26 is capable of rotatable engagement within the slot 17 and is terminated by a head 28 rotatably disposed within the recess 18, and engageable with the bottom thereof to prevent the longitudinal removal 50 of the yoke from the front housing 10.

The arm 27 is conveniently machined to permit its introduction within the slot 19 through the opening 20. The outer end portion of this arm is bent at right angle to afford a tongue 29 capable of engagement within the recess 23.

Opening into the recess 18, there is provided within the wall of the front housing 10, a square bore 30, within which is slidably disposed a square plunger 31. This plunger by virtue of its square cross section within a corresponding bore is held 60 against rotation and has its end, adjacent the opening of the bore 30, provided with a transversely disposed lug or rib 32. The head 28 of the retainer arm 26 is provided with two transversely disposed grooves 33, within which the rib 65 32 is capable of engagement and may be maintained therein by the pressure exerted by a compression spring 34 which is disposed within the bore 30, rearwardly of the plunger 31. The square plunger 31 is located within the corresponding bore 30 in such a manner as to afford 70 the engagement of the rib 32 within one of the grooves 33 when the yoke 24 is positioned as illustrated in Fig. 3 and Fig. 4. The frictional engagement of the rib 32 with the side wall of 75 the grooves 33, affords an efficient locking device for the yoke, preventing thereby its accidental shifting from the operative position to the inoperative position.

Diametrically opposed to the square bore 30, 80 there is provided, within the wall of the front housing 10, a bore 35 terminated by a restricted screw threaded portion 36. Slidably disposed within the bore 35, there is a plunger 37 which is attached in any suitable manner, as for instance 85 by means of cement, to a resilient member 38, preferably made of rubber. This member and consequently the plunger 37 are secured within the bore 35 by a screw 39 in engagement within the restricted screw threaded portion 36. That 90 screw may be secured to the member 38 in any suitable manner, it may for instance be vulcanized therein. The plunger 37 protrudes a convenient amount from the bore 35 and has its protruding end beveled to permit the passage of 95 the tongue 29.

When the retainer is shifted into an operative position, the tongue 29 being in engagement upon the lug 22 will pass under the plunger 37 by compressing the resilient member 38. 100 Subsequently the tongue 29 will fall into the groove 23 and will be maintained therein by the pressure exerted by the plunger 37, thus cooperating with the locking device provided upon the head 28 to prevent the accidental shifting of the 110

yoke from an operative into an inoperative position. When the yoke 24 is in the operative position, the drill is prevented from sliding outwardly from the front head 10 by the engagement of the loop 25 with the collar 15. When it is desired to remove the tool from the drill, the retainer or yoke 24 may be positioned as illustrated in Fig. 4, by forcing the tongue 29 out of engagement from the recess 23, and the rib 32 out of engagement from one of the grooves 33. The retainer will be locked into the opened position by the frictional engagement of the rib 32 within the other of the grooves 33. In this last mentioned position of the yoke the plunger 35 is retained within the bore 35 by its association with the member 38 as previously explained.

During the drilling operation, it is often necessary for the operator to continue such operation until the lower face of the yoke becomes in contact with the surface of the material being drilled, thus imparting an upward pressure upon the yoke and tending to cause the disengagement of the tongue 29 from the recess 23 and allow the accidental shifting of the retainer into an inoperative position. This detrimental feature is overcome by the engagement of the rib 32 within one of the grooves 33. Any forces acting in an upward direction will have the tendency to further compress the spring 34 and consequently increase the pressure of the plunger 31 or increase the frictional engagement of the rib 32 within the corresponding groove 33, thus preventing accidental shifting of the retainer into an inoperative position.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

45 I claim:

1. In a drill retainer, a front head having a bore for receiving the drill, a grooved lug integral with said front head, a yoke having arms integral therewith, one of said arms being terminated by a head rotatably mounted within a recess provided within said front head, said head pivotally securing said yoke to said front head, the other of said arms being bent to form a tongue engageable within the groove of said lug to lock said yoke in operative position, and means resiliently engageable with said tongue to effect pressure thereon for maintaining said tongue within said groove.

2. In a drill retainer, a front head having a bore to receive the drill, a yoke having arms integral therewith and being pivotally secured to said front head by one of said arms, and opening within said front head through which the other of said arms may pass to position said yoke into operative or inoperative relation with respect to said drill, and locking means capable of

engagement with each of said arms to hold said yoke in operative position.

3. In a drill retainer, a front head having a bore to receive the drill, a yoke having arms integral therewith and being pivotally secured to said front head by one of said arms, an opening within said front head through which the other of said arms is free to pass for locating said yoke into operative or inoperative position, locking means capable of engagement with each of said arms to hold said yoke in operative position and with one of said arms to hold said yoke in inoperative position.

4. In a drill retainer, a front head having a bore for receiving the drill, a grooved lug integral with said front head, a yoke having arms extending upwardly therefrom, said yoke being pivotally secured to said front head by the extremity of one of said arms, the other of said arms being formed with a tongue engageable with the groove of said lug to lock said yoke in operative position, and means resiliently engageable with said tongue to effect pressure thereon for maintaining said tongue within said groove.

5. In a drill steel retainer, a housing having a bore for receiving the shank of a collared drill steel, a counterbore within which the collar of said drill steel is free to slide, a yoke having arms extending upwardly therefrom, means for pivotally securing said yoke to said housing by one of said arms, said yoke being normally located adjacent the front end of said housing for engagement with the collar of said drill steel, and further means permitting the passage of the other of said arms away from said housing when said yoke is shifted from operative into inoperative position.

6. In a drill steel retainer, a housing having a bore for receiving the shank of a drill steel, a collar on said drill steel, a counterbore within said housing within which said collar is free to slide, a yoke moving a duality of arms integral therewith, said arms being substantially entirely within said housing when said yoke is positioned for operative engagement with said collar, means for pivotally securing said yoke to said housing by one of said arms, and further means permitting the passage of the other of said arms away from said housing when said yoke is shifted from operative into inoperative position.

7. In a drill steel retainer, a housing having a bore for receiving the drill, a yoke having arms extending upwardly therefrom, said yoke being suspended into operative engagement with said drill to said housing by one of said arms pivotally secured in the interior of said housing, the other of said arms being capable of engagement with said housing for cooperating in the suspension of said yoke, and a passage within said housing through which said last mentioned arm is free to pass when said yoke is shifted from operating into inoperating position.

JOHN C. CURTIS. 140
